UNITED STATES PATENT OFFICE

2,018,296

PENCIL ATTACHMENT

Peter Clow, Easton, Pa., assignor of one-tenth to
 Paul Bleika and one-third to Israel Krohn,
 both of Easton, Pa.

Application August 29, 1934, Serial No. 741,975

3 Claims. (Cl. 120—35)

This invention relates to improvements in pencil attachments and has for its principal object the provision of a novel form of paper cutting attachment.

5 Another object is to provide a paper cutting attachment which can be embodied in a pencil holder, the assembly being such that it can be produced at a relatively low cost.

A still further object is to provide a paper cutting attachment for pencil holders wherein the major portion of the cutting element is confined within the holder while that portion of said element which is utilized for cutting is protected, so to speak, by being located below the normal surface of the holder.

10 A still further object is to provide a paper cutting attachment for pencil holders which, when not in use, is covered by an eraser frictionally retained on the exterior surface of the holder.

20 With these and other objects in view the invention consists in certain details of construction and combinations and arrangements of parts all as will hereinafter be more fully described and the novel features thereof particularly pointed out in the appended claims.

In the accompanying drawing,—

Figure 1 is a perspective view illustrating a pencil holder with the eraser thereon;

Fig. 2 is a similar view with the eraser removed; 30 and

Fig. 3 is a sectional view longitudinally of the holder.

The holder 10 is preferably of cylindrical cross-section throughout the greater portion of its 35 length, but is tapered or of conical shape at one end as at 11. Its opposite end, as usual, is open for insertion of the pencil 12. The tapered end 11 is provided in its side with a slot 13, and secured within the holder is a cutting element or blade 14, 40 a portion 14a of whose cutting edge protrudes through said slot. Preferably, said cutting element is a thin blade of rectangular shape, one corner at one end engaging against the inner surface of the conical portion 11 of the holder and the other corner at said end projecting through said slot. At its opposite end the cutting element is seated firmly on a block 15 frictionally secured in the holder. With a corner of said element protruding through the slot, two contiguous edges of 50 said element engage the ends of the slot, thus aid-

ing to the rigid mounting of the element. Said block may be of any desired material, but is preferably somewhat resilient. With this arrangement, element 14 is securely held in position with its corner 14a exposed at the exterior of the holder. It will be observed that only a small portion of the cutting edge of said element is exposed so as to reduce the possibility of anyone severely cutting himself. Furthermore, that portion of the cutting edge projecting through slot 13 is of such 10 length as to terminate below the normal surface of the holder, thus further reducing liability of injury. In other words, by forming the tapered end portion 11 on the holder, the cylindrical portion serves as a guard for the exposed corner 14a 15 of the blade.

When the cutter is not in use it should be covered or protected. This is preferably accomplished by providing a cover in the form of an eraser 16, provided with a tapered socket whereby 20 the eraser can be frictionally secured on the tapered end 11 of the holder, but can be readily removed if, and when, it is desired to use the cutter. Thus, the present cutter attachment can be manufactured at a low cost, due to the simplicity of its 25 construction and assembly and, as also pointed out, the cutting element is thoroughly protected.

What is claimed is:

1. A paper cutting attachment for pencils consisting of a tubular metallic holder having a 30 tapering end with a slot in one side thereof, and a cutting element enclosed within said holder, a portion of the cutting edge of said element protruding through said slot.

2. A paper cutting attachment for pencils consisting of a tubular holder having a tapering end with a slot in the side of said tapering portion, and a cutting element secured within said holder with a portion of its cutting edge projecting through said slot but terminating below the side surface 40 of the enlarged portion of said holder.

3. A paper cutting attachment for pencils consisting of a tubular metallic holder having a tapering end portion with a slot in one side of said end portion, and a cutting element enclosed with- 45 in said holder, one corner of said element protruding through said slot with two contiguous edges of said element abutting the ends of the slot.
